Inventor

Lucas C. Clark

United States Patent Office.

LUCAS C. CLARK, OF PLANTSVILLE, CONNECTICUT.

Design No. 3,586, dated July 27, 1869.

DESIGN FOR A TEAPOT-HANDLE.

The Schedule referred to in these Letters Patent and making part of the same.

To all whom it may concern:

Be it known that I, LUCAS C. CLARK, of Plantsville, in the county of Hartford, and State of Connecticut, have originated and designed a new Design for Teapot-Handles, of which the following is a full, clear, and exact description, reference being had to the accompanying drawings, making part of this specification, in which—

Figure 1 is a side elevation of my design.

Figure 2 is a section of the same, on line *x-y*.

My invention relates to the body, or main portion of the handle.

The general form of the handle is the same as ordinary teapot-handles. Each edge of the handle is composed of a band, *A A*, slightly rounded on each side, and connected together by a thin plate, *B*, in

such manner that the body of the handle is bordered by ribs *a a*, between which is a recess, *b*, while a transverse section of any portion of the handle, except the extreme ends, forms a figure similar to the letter *H*, as shown in fig. 2, thus producing a design of plain and neat appearance, and one which can be easily cast, and is light to handle.

What I claim as new, and desire to secure by Letters Patent is—

The design for the main portion of a handle for teapots and similar vessels, herein shown and described.

LUCAS C. CLARK.
